WEARING APPAREL

James R. Hibshman, Cleveland Heights, Ohio,
assignor to Harold V. Ensten

Application March 10, 1937, Serial No. 130,059

12 Claims. (Cl. 2—90)

My invention relates to wearing apparel and more particularly to wearing apparel in the general form of a vest.

An object of my invention is to provide a knitted wearing apparel in the general form of a vest.

Another object of my invention is to provide for making a wearing apparel in the general form of a vest from a strip of material having portions which are angularly positioned relative to other portions of the strip.

Another object of my invention is to provide for making wearing apparel in the general form of a vest of a continuous strip of material; folded and joined in such fashion as to avoid substantially any waste in the material.

Another object of my invention is to provide for making wearing apparel in the general form of a vest from a continuous strip of rack-knitted material having an angularly shaped central portion and two angular extension portions and having the intermediate part of the central portion and the two ends of the angular extension portion secured together.

Other objects and a fuller understanding of my invention may be had by referring to the following description and claims, taken in combination with the accompanying drawings, in which like parts are designated by like reference characters, and in which:

Figure 1 shows a front view of my wearing apparel as it appears on a person;

Figure 2 is a rear view of my wearing apparel as it appears on a person;

Figure 3 shows a fragmentary end view of a continuous strip of material from which my wearing apparel may be constructed;

Figure 4 shows a section cut from a continuous strip of material, adapted for use in making the wearing apparel shown in Figures 1 and 2;

Figure 5 shows a rear view of my wearing apparel, preparatory to joining the several portions together;

Figure 6 shows a front view of a modified form of my wearing apparel as it appears upon a person;

Figure 7 shows a rear view of my modified wearing apparel as it appears upon a person;

Figure 8 shows a strip of material for making my modified wearing apparel as shown in Figures 6 and 7;

Figure 9 shows a rear view of the wearing apparel shown in Figures 6 and 7, preparatory to joining the several portions thereof;

Figure 10 shows a front view of another modified

form of my wearing apparel as it appears upon a person;

Figure 11 shows a rear view of my wearing apparel in Figure 10, as it appears upon a person;

Figure 12 shows a strip of material for making the wearing apparel shown in Figures 10 and 11;

Figure 13 shows a rear view of my wearing apparel in Figures 10 and 11, preparatory to joining the several portions together;

Figure 14 shows a front view of another modified form of my wearing apparel as it appears upon a person;

Figure 15 shows a rear view of my wearing apparel in Figure 14 as it appears upon a person;

Figure 16 shows a strip for making the wearing apparel shown in Figures 14 and 15; and

Figure 17 shows a rear view of the wearing apparel in Figures 14 and 15, preparatory to joining the several portions together.

With reference to Figures 1 and 2, my wearing apparel in the general form of a vest, may be made from a strip of material having portions angularly positioned relative to other portions, as indicated generally by the reference character 20. This strip 20 may be cut from a continuous strip of rack-knitted material as indicated in Figures 3 and 4. As illustrated, the continuous strip is zig-zagged and the width measured transversely of its general length is substantially everywhere the same, and the edges thereof have continuous selvage to prevent raveling. The particular continuous strip here described and shown may be made on a flat bed knitting machine as follows: First by "racking" each course successively in one direction to make the first length and then by reversing the direction of the "racking" until next length is knitted. This same method is employed to make each successive length. The machine is operated continuously and is so constructed that the "racking" can be reversed automatically. Therefore, in making my wearing apparel, in the general form of a vest, the strip is knitted to the desired shape and as will appear there is substantially no cloth or yarn wasted in making my wearing apparel.

After the continuous strip of rack-knitted material is made, it is then severed into the individual strips 20. A single severed strip 20 comprises two substantially rhomboidal side portions 22 and 23; two substantially rhomboidal extension portions 21 and 24, and two intermediate sharply zig-zagged portions 25 and 26. The reference character 31, having the ends 32 and 33,

designates a rack-knitted line between the two substantially rhomboidal side portions 22 and 23. The front edge of the rhomboidal side portion 22 is designated by the reference character 34 and the rear edge by the reference character 38. The front edge of the rhomboidal side portion 23 is designated by the reference character 35 and the rear edge by 39. The rear edge of the intermediate sharply zig-zagged rack-knitted portion 25 is designated by the reference character 40 and the front edge by 36. The rear edge of the intermediate sharply zig-zagged rack-knitted material 26 is designated by the reference character 41 and the front edge by 37. The line 42, having the ends 44 and 45, designates the severed end of the substantially rhomboidal extension portion 21 and the line 43 having the ends 46 and 47 designates the severed end of the substantially rhomboidal extension portion 24. The front edge of the substantial rhomboidal extension portion 21 is designated by the reference character 50 and the front edge of the substantially rhomboidal extension portion 24 is designated by the reference character 51.

25 In assembly of the severed strip 20 of Figure 4 into a wearing apparel having the general form of a vest, the portion of the strip in the region where the inner ends of the two substantially rhomboidal sides 22 and 23 are connected together, fit the back below the neck and the shoulders. The remaining portion of each of the two substantially rhomboidal side portions 22 and 23 fit respectively over each shoulder and downwardly over the upper part of the chest. The portion of the strip 20 in the region of the intermediate sharply zig-zagged portions 25 and 26 fit a lower part of the chest. Each of the extension portions 21 and 24 pass under the arms respectively and have their outer ends 42 and 43 connected to each other and to the edges 38 and 39, respectively, making the seams 54 and 55. In joining the several portions of the continuous strip 20, the points 45 and 47 are arranged to coincide substantially with the point 32. The front edges 50 and 51 are joined for a certain distance to the points 52 and 53, making a seam 56.

As illustrated in Figure 5, sections 61 and 62 are cut away, and the cut away edges formed thereby are joined making the seams 59 and 60 as shown in Figure 2 of the drawings. This is done in order to make a good fitting garment. The seams may be produced by a sewing operation, which has combined therewith an overcasting operation to produce a smooth job. The front of my wearing apparel in the general form of a vest, may be held together in the usual manner by means of button holes 57 and the buttons 58. In the making of my wearing apparel in the general form of a vest in Figures 1 and 2, there is substantially no waste to the material, except the two sections 61 and 62 which are cut out to make a good fitting garment. The edges 34 and 35 may be rolled as indicated in Figures 1 and 2 to give a neat appearance.

In Figures 6, 7, 8, and 9, I show a modified form of my invention, particularly in the manner in which the several portions of the strip 20 are joined together. In making the garment shown in Figures 6 and 7, the strip 20 in Figure 8 is used, being the same strip as shown in Figure 4, but the angular ends of the substantially rhomboidal extension portions 21 and 24 are cut off as indicated by the lines 65 and 66, respectively, making the corners 45 and 67 and 47 and

68. These two severed ends 65 and 66 are joined as indicated in Figures 7 and 9, making the seam 69 and causing the corners 45 and 47 to coincide at the lower edge of the back band of the garment and the corners 67 and 68 to coincide at the upper edge of the back band of the garment. The tip 32 of the central back portion of the substantially rhomboidal sides 22 and 23, is then joined to the back band in the region of the corners 67 and 68, making the seams 70 and 71. This modified form exposes a portion of the back of the person which adds to the novelty of the general lines of vests embodying my invention. Also it is to be observed in the making of the vest shown in Figures 6 and 7 that there is substantially no waste in the material except the two angular ends which are cut off the substantial rhomboidal extensions 21 and 24.

In Figures 10, 11, 12, and 13 I show a further modified form of my invention, particularly with reference to a modification of the general arrangement and shape of the strip 74 of Figure 12 from which the vests are made. In this modified form, an intermediate sharply zig-zagged central portion 75 is rack-knitted between the inner ends of the two substantial rhomboidal side portions 22 and 23. The front edge of the intermediate portion 75 is indicated by the reference character 77 and the rear edge by the reference character 78. The rack-knitted line between the substantially rhomboidal portions 21 and 22 is indicated by the reference character 79 and the rack-knitted line between the substantially rhomboidal portions 23 and 24 is indicated by the reference character 80. Each end of the substantial rhomboidal extension portions 21 and 24 of Figure 12 are cut off the same as they were in Figure 8.

The two severed ends 65 and 66 are joined as indicated in Figures 11 and 13, making the seam 80, and causing the corners 45 and 47 to coincide at the lower edge of the back band of the garment and the corners 67 and 68 to coincide at the upper edge of the back band of the garment. The rear edge 76 of the intermediate portion 75 is then joined to the upper edge of the band of the garment, making a seam 81. In the making of the vest shown in Figures 10 and 11, there is substantially no waste in the material except the two angular ends which are cut off the substantially rhomboidal extensions 21 and 24.

In Figures 14, 15, 16, and 17, I show a further modified form of my invention, and particularly with reference to a modification of the general arrangement and shape of the strip 83 of Figure 16 from which the vests are made. In this form, the substantially rhomboidal side portions 22 and 23 are the same as shown in Figures 4 and 8, but the extensions, identified in Figure 16 as 84 and 85 are sharply zig-zagged and extend substantially horizontal from the ends of the rhomboidal side portions 22 and 23.

The front edge of the extension 84 is indicated by the reference character 88 and the rear edge 86, and the front edge of the extension 85 by 89 and the rear edge by 87. A portion of the end 90 of the extension 84 is joined to the edge 38, making a seam 92, and a portion of the end 91 of the extension 85 is joined to the edge 39, making a seam 93. The remaining portions of the ends 90 and 91 are joined, making a seam 94. As illustrated, sections 95 and 96 are cut away, and the cut away edges formed thereby are joined making the seams 97 and 98 shown

under the arms. In the making of my wearing apparel in Figures 14 and 15, there is substantially no waste of the material except the cut away sections 95 and 96, which is very small. In 5 all the forms of my garments, they may be held together on a person by button holes 57 and buttons 58. Thus, it is seen that I have produced a garment in the general form of a vest from a strip of material; folded and joined in 10 such fashion as to avoid substantially any waste in the material.

Although I have described my invention with a certain degree of particularity, it is understood that the present disclosure has been made only 15 by way of example and that numerous changes in the details of construction and the combination and arrangement of parts may be resorted to without departing from the spirit and the scope of the invention as hereinafter claimed.

20 I claim as my invention:

1. A wearing apparel comprising a strip angularly shaped to form a vest, said strip having a substantially V-shaped central portion and two extension portions, said substantially V-shaped 25 central portion having two sides connected together at their inner ends, each of said extension portions being respectively and angularly connected to the ends of the sides of the substantially V-shaped central portion, the portion of 30 the strip in the region where the inner ends of the two sides of the substantially V-shaped central portion are connected together fitting the back below the neck and the shoulders, the remaining portion of each of said two sides of the 35 substantially V-shaped central portion fitting respectively over each shoulder and downwardly over the upper part of the chest, the portion of the strip in the regions where each of the said extension portions is respectively connected to 40 the ends of the sides of the substantially V-shaped central portion fitting a lower part of the chest, the remaining portion of each of said extension portions passing under the arms respectively and being connected to each other and to the said 45 portion of the strip fitting the back below the neck and the shoulders.

2. A wearing apparel comprising a strip angularly shaped to form a vest, said strip having a central portion and two extension portions, said 50 central portion having two sides angularly connected together at their inner ends, each of said extension portions being respectively and angularly connected to the ends of the sides of the central portion, the portion of the strip in the region where the inner ends of the two sides of the central portion are connected together fitting the back below the neck and the shoulders, the remaining portion of each of said two sides of the 55 central portion fitting respectively over each shoulder and downwardly over the upper part of the chest, the portion of the strip in the regions where each of the said extension portions is respectively connected to the ends of the sides of the central portion fitting a lower part of the chest, the remaining portion of each of said extension portions passing under the arms respectively and being connected to each other and to the said portion of the strip fitting the back below the neck and the shoulders.

70 3. A wearing apparel comprising a strip angularly shaped to form a vest, said strip having a central portion, two interconnecting portions, and two extension portions, said central portion having two sides angularly connected together at 75 their inner ends, each of said interconnecting

portions having an inner end respectively and angularly connected to the ends of the sides of the central portion, each of said extension portions having an end respectively and angularly connected to the outer ends of the interconnecting portions, the portion of the strip in the region where the inner ends of the two sides of the central portion are connected together fitting the back below the neck and the shoulders, the remaining portion of each of said two sides of the 10 central portion fitting respectively over each shoulder and downwardly over the upper part of the chest, the portion of the strip in the region of the interconnecting portions fitting a lower part of the chest, and each of the said extension 15 portions passing under the arms respectively and having their outer ends connected to each other and to the said portion of the strip fitting the back below the neck and shoulders.

4. A wearing apparel comprising a strip angularly shaped to form a vest, said strip having a central portion and two extension portions, said central portion having an intermediate portion and two sides, the inner end of each of the two sides being angularly and respectively connected to each end of the intermediate portion, the inner end of each of said extension portions being respectively and angularly connected to the ends of the sides of the central portion, the portion of the strip in the region of the intermediate portion fitting the back below the neck, each of said two sides of the central portion passing over each shoulder respectively and downwardly over the upper part of the chest, the portion of the strip in the region where each of the said extension portions is respectively connected to the ends of the sides of the central portion fitting a lower part of the chest, the remaining portion of each of said extension portions passing under the arms respectively and being connected to each other and to the said intermediate portion fitting the back below the neck.

5. A wearing apparel comprising a strip angularly shaped to form a vest, said strip having a substantially V-shaped central portion and two extension portions, said substantially V-shaped central portion having two substantially rhomboidal sides connected together at their inner ends, each of said extension portions being respectively and angularly connected to the ends of the two substantially rhomboidal sides of the substantially V-shaped central portion, the portion of the strip in the region where the inner ends of the two substantially rhomboidal sides of the substantially V-shaped central portion are connected together fitting the back below the neck and the shoulders, the remaining portion of each of said two substantially rhomboidal sides of the substantially V-shaped central portion fitting respectively over each shoulder and downwardly over the upper part of the chest, the portion of the strip in the regions where each of the said extension portions is respectively connected to the ends of the substantially rhomboidal sides of the substantially V-shaped central portion fitting a lower part of the chest, the remaining portion of each of said extension portions passing under the arms respectively and being connected to each other and to the said portion of the strip fitting the back below the neck and the shoulders.

6. A wearing apparel comprising a strip angularly shaped to form a vest, said strip having a central portion and two extension portions, said central portion having an intermediate portion

- and two substantially rhomboidal sides, the inner end of each of the two substantially rhomboidal sides being angularly and respectively connected to each end of the intermediate portion, the inner 5 end of each of said extension portions being respectively and angularly connected to the ends of the substantially rhomboidal sides of the central portion, the portion of the strip in the region of the intermediate portion fitting the back below 10 the neck, each of said two substantially rhomboidal sides of the central portion passing over each shoulder respectively and downwardly over the upper part of the chest, the portion of the strip in the region where each of the said extension portions is respectively connected to the ends of the substantially rhomboidal sides of the central portion fitting a lower part of the chest, the remaining portion of each of said extension portions passing under the arms respectively and 15 20 being connected to each other and to the said intermediate portion fitting the back below the neck.

7. The process of making a vest which comprises forming a strip having a flat generally V-shaped central portion and two angular extension portions, and joining the intermediate part of the central portion to the two end edges of the extension portion.

8. A wearing apparel comprising a continuous strip shaped to form a vest, said strip having a central generally V-shaped portion and two extension portions angularly connected to the ends of the central portion, the intermediate part of the central portion fitting the back below the neck and the shoulders and the remaining part of the central portion fitting over each shoulder and downwardly over the upper part of the chest, the part of the strip in the region where each of said extension portions is respectively connected to the ends of the central portion fitting a lower part of the chest, the remaining part of each of said extension portions passing under the arms respectively and being connected to each other.

9. A wearing apparel comprising a continuous strip shaped to form a vest, said strip having a generally V-shaped central portion and two extension portions angularly connected to the ends of the central portion, the intermediate part of the central portion fitting the back below the neck and the shoulders and the remaining part of the central portion fitting over each shoulder and downwardly over the upper part of the chest, the part of the strip in the region where each of said extension portions is respectively connected to the ends of the central portion fitting a lower part of the chest, the remaining part of each of said extension portions passing under the arms

respectively and being connected to each other and to the said intermediate part of the central portion fitting the back below the neck and the shoulders.

10. A wearing apparel comprising a knitted material shaped to form a vest, said material having a central portion with two spaced sides and two extension portions angularly and respectively connected to the ends of the said sides, the intermediate part of the central portion fitting the back below the neck and the shoulders, and the spaced sides respectively fitting over each shoulder and downwardly over the upper part of the chest, the part of the material in the region where each of the said extension portions is respectively connected to the ends of the spaced sides fitting a lower part of the chest, the remaining part of said extension portions being connected together and fitting under the arms and around the back.

11. A wearing apparel comprising a knitted material shaped to form a vest, said material having a central portion with two spaced sides and two extension portions angularly and respectively connected to the ends of the said sides, the intermediate part of the central portion fitting the back below the neck and the shoulders, and the spaced sides respectively fitting over each shoulder and downwardly over the upper part of the chest, the part of the material in the region where each of the said extension portions is respectively connected to the ends of the spaced sides fitting a lower part of the chest, the remaining part of said extension portions being connected together and fitting under the arms and around the back, and being connected to said intermediate part of the central portion fitting the back below the neck and shoulders.

12. A wearing apparel comprising a knitted material shaped to form a vest, said material having a central portion and an extension portion, the intermediate part of the central portion fitting the back below the neck and shoulders, said central portion having two spaced sides fitting the shoulders and the upper part of the chest, said extension portion having a first part fitting a lower part of the chest, two portions constituting a second part fitting the sides of the body under the arms and a third part fitting the back, the third part of the extension portion fitting the back being connected to the central portion and each of the two portions of the second part of the extension portion fitting the sides of the body under the arms being respectively an angular continuation of the said spaced side which fits over the shoulder on the same side of the body.

JAMES R. HIBSHMAN.
